James Irwin Gemmill, ^{INVENTOR}

UNITED STATES PATENT OFFICE.

JAMES I. GEMMILL, OF CLEVELAND, OHIO, ASSIGNOR TO THE GEMMILL TELEPHONE AND MANUFACTURING CO., OF ORRVILLE, OHIO.

AUTOMATIC ANNUNCIATOR-RESTORER.

SPECIFICATION forming part of Letters Patent No. 787,507, dated April 18, 1905.

Application filed December 22, 1902. Serial No. 136,279.

To all whom it may concern:

Be it known that I, JAMES IRWIN GEMMILL, a citizen of the United States, residing at Cleveland, in the county of Cuyahoga and State of Ohio, have invented certain Improvements in Automatic Annunciator-Restorers; and I do hereby declare that the following is a full, clear, and exact description of my invention, which will enable others skilled in the art to which it appertains to make and use the same, reference being had to the accompanying drawings, and to the characters of reference marked thereon, which form part of this specification.

The object of my invention is to obtain a mechanical movement, actuated by the well-known switchboard-plug, to restore the drop-shutter on telephone-switchboards automatically and to reduce the wear and friction in the device to a minimum. To this end I have invented a toggle system of balls or rollers, so placed that friction is overcome by the rounded surfaces rolling over each other instead of rubbing-surfaces, which are used in the devices at present known.

Reference being had to the drawings, Figure 1 represents a well-known form of switchboard-drop, partially in section and partially in elevation, equipped with my new device. Figs. 2 and 3 are two views of my device shown in connection with a switchboard-plug, being partially in section and partially in elevation. Figs. 4 and 5 are diagrammatic views of the device, showing how it is possible to actuate the shutter by contact with one of the rolling members, omitting the link or bolt. Fig. 6 is a view of the sleeve of the jack 5, with the bolts 14 shown in section through line N S, Fig. 3.

Referring to the reference characters in the drawings in a more particular description of the device, it will be noticed that Fig. 1 represents a common and well-known form of an armored electromagnet-coil, with the armature 2, adapted to be influenced by the said coil and actuate the detent 3 to unhook the

shutter 4 and allow it to fall when the electromagnet has been energized by a suitable current from the line.

5 5 designate a well-known form of spring-jack, with contacts and spring connections suitably arranged to meet the requirements of the system to which same may be attached.

As the details of the electromagnetic mechanism and functions of the same, together with 55 the spring-jack, are well understood by those skilled in telephony, it is not necessary to describe same any more than to show their connection with my restoring device.

In the restoring device I employ three balls 60 or rollers 6, 7, and 8, Fig. 1. The ball or rolling member 6 is used as the fixed or stationary member or point in the toggle system. The rolling member 7 is adapted to project partially through the containing-receptacle 10 in the path provided for the plug in the jack 5. A third ball, 8, completes the system of rolling members. A bolt or pin 9 serves to transfer the motion imparted to the ball 8 to the lower edge or extension of 70 the shutter 4. Said shutter 4 turns freely on the pivot 11 upon being released by the detent 3. It then assumes a horizontal position, (shown at 4'). The plug 12 is then inserted into the jack to answer the call. The plug 75 12, traveling in the jack, meets the member 7, which is resting on the pins 14, and forces the said member 7 upward between the stationary member 6 and the moving member 8, which by reason of the resistance of the walls 80 of the chamber 10 causes the member 8 to travel in a direction opposite that of the actuating-plug 12. The member 8 through the agency of the pin 9 imparts motion to the shutter 4. The shutter consequently turns 85 upward on the pivot 11, and the upper edge engages with the detent 3, staying in this position after the plug is removed, the shutter remaining in this position until thrown down by a call. It is obvious that the member 8 90 may be made to act directly upon the shutter 4, as shown in Figs. 4 and 5. Points *xxx*

are shown to indicate resistance-points for the toggle system in lieu of the walls of the receptacle 10, which is not shown in these figures. In Figs. 1, 2, and 3 the pin 13 serves 5 to retain the member 6 in its respective position in the chamber. In Fig. 2 the pin 14 apparently would interfere with the plug passing through the jack; but that is obviated, as shown in Fig. 6, which discloses the pins 14 10 14, one on each side of the sleeve of the jack. The said pins are fitted into and adapted to slide in receptacles 14' 14'. Spiral springs serve to project the said pins into the said jack far enough to support the member 7 15 when the plug is absent, and so prevent the member 7 from falling into the sleeve of the jack. The plug after engaging the member 7 proceeds, and in so doing slides the pins in out of the way, leaving a free passage for the 20 plug. It is obvious that were a sphere used as member 7 of this combination, retaining the adjustment of the pins 14 14, as shown in Fig. 6 of the disclosure, the whole mechanism would become inoperative through the 25 sphere 7 becoming wedged between the said pins 14 14. The pins, as shown, are arranged to support the member 7 as a disk, and in the substitution of a sphere therefor the pins 14 14 should be set out in the jack 5 in a manner 30 as would result by an elongation of the spiral springs, and thereby bring the adjacent ends of the pins within the jack more closely together, and thereby make it impossible for the member 7 as a sphere to enter between the 35 said pins by reason of its weight and rounded sides and therein becoming wedged, and so become inoperative. As it is possible to omit the bolt 9 from this restoring device, I therefore do not limit myself in my claims 40 to the construction including the bolt, as shown in Figs. 2 and 3.

The three rolling members of my system may be either balls, rollers, or suitable disks. I can therefore use any one of the above forms 45 of rolling members and still retain the elementary principle of my device—namely, the use of rolling or rounded surfaces to diminish friction and wear.

Now, having thus fully described my device, 50 what I claim as new, and wish to secure by Letters Patent, is—

1. In an indicator device, the combination of a pivoted shutter adapted to fall to a horizontal position to display a signal; an extension on said shutter and an intermediate pin 55 adapted to engage said extension; a train of three balls, one of said balls adapted to operate said pin; one adapted to engage the rear walls of the ball-containing chamber; the third ball being placed between the aforementioned two balls and adapted to lie partially in the path of a restoring-plug to be operated by said plug and to coöperate with the aforementioned

two balls causing one of the said balls to engage the pin and actuate it so that the said 65 pin will engage the said shutter by means of the extension thereon and thereby restore said shutter to its normal position all as shown and described.

2. In a switchboard, the combination with 70 a jack and a drop, of a plurality of circular bodies, one of said bodies being stationary, a second being operatively related to the drop, and a third adapted to be forced between the other two bodies by the insertion of the operator's plug into the jack, thereby restoring 75 the drop substantially as described.

3. In a signal-restoring device for switchboards; a toggle system of three rolling bodies together with a bolt and a drop-shutter; one 80 of the rolling bodies adapted to act against the rear walls of the containing-chamber as a fixed or stationary member of the said toggle system; one body as a traveling member adapted to engage and actuate the bolt and 85 the third body adapted to be forced between the other two bodies thereby imparting motion to the traveling member and the bolt causing said bolt to engage said shutter and restore it to its normal position. 90

4. In a switchboard-drop; the combination of a drop-shutter with an extension thereon and a bolt adapted to engage with said extension; a ball adapted to act against said bolt; a second ball adapted to act against fixed points 95 or surfaces and a third ball adapted to be placed partially in the path of an operator's plug, in a jack, suitably placed; said plug to engage said ball in the jack and force it between the said two balls, thereby elongating the toggle 100 system and imparting motion to the bolt; said bolt engaging said extension on the shutter and thereby restoring said shutter to its normal position, all as shown and described.

5. In switchboard-annunciators, in combination with a jack, a connecting-plug, a pivoted signal-drop, and an independent rolling, drop-moving member, and means whereby 105 said member may be actuated by said plug.

6. In switchboard-annunciators, in combination with a jack, a pivoted signal-drop, a connecting-plug, and an independent antifriction drop-moving member bodily movable from point to point and means whereby said plug may be pressed against said member and 110 the drop actuated.

7. In a switchboard-annunciator, in combination with a jack, a drop, a connecting-plug, a rolling, drop-restoring member between said 115 plug and drop and means whereby the said member moves back by its own weight to position to permit the drop to be released.

8. In a switchboard-annunciator in combination with a pivoted signal-drop, and plug, a drop-restoring device consisting of a ball 125 operative between said drop and plug.

9. In a switchboard-annunciator in combination with a jack, a drop, and a plug, said jack having a slot and a loose, drop-restoring ball supported by said jack in said slot
5 and adapted to project therethrough partially into the jack and having a limited to-and-fro movement between the jack and said drop.

In witness whereof I have, this 27th day of March, A. D. 1902, affixed my signature in the presence of two subscribing witnesses.

JAMES I. GEMMILL.
